(57) **CLAIM**

The ornamental design for a combined trash receptacle and windshield service center, as shown and described.

DESCRIPTION

FIG. 1 is a perspective view of a combined trash receptacle and windshield service center showing my new design;

FIG. 2 is a front view thereof;

FIG. 3 is a right side view thereof; the left side being a mirror image thereof;

FIG. 4 is a back view thereof;

FIG. 5 is a top view thereof; and,

FIG. 6 is a bottom view thereof.

The broken line showing of some elements in the figures is included for the purpose of illustrating portions of the receptacle and forms no part of the claimed design.
